UNITED STATES PATENT OFFICE.

PETER J. LEONARD AND FRED J. CONNOR, OF WORCESTER, MASSACHUSETTS, ASSIGNEES, BY MESNE ASSIGNMENTS, TO THE CHASE NATIONAL BANK OF THE CITY OF NEW YORK, OF NEW YORK, N. Y.

FLOUR SIFTER.

Application filed February 2, 1924. Serial No. 690,266.

This invention relates to a flour sifter of the type commonly used for domestic purposes, it being the object of our invention to provide certain improvements in the construction of such sifters by which a more satisfactory and reliable article will be produced.

With this general object in view, an important feature of our invention relates to the provision of an improved beater or agitator for the sifter, which is of novel construction and which is very efficient in operation.

Another feature of our invention relates to the provision of an improved screen holder in which the rough edges of the screen are entirely covered and by which the screen is securely held in operative position.

Our invention further relates to certain arrangements and combinations of parts which will be hereinafter described and more particularly pointed out in the appended claims.

A preferred form of the invention is shown in the drawings in which

Fig. 1 is a sectional side elevation of our improved sifter;

Fig. 2 is a sectional elevation showing the construction of the beater or agitator;

Fig. 3 is a detail side elevation showing the joint used in forming the beater;

Fig. 4 is a detail sectional view taken along the line 4-4 in Fig. 3;

Figs. 5, 6 and 7 are detail views showing successive steps in assembling the screen and its supporting rim or holder; and

Fig. 8 is a detail sectional view of the sifter handle, taken along the line 8-8 in Fig. 1.

Referring to the drawings, we have shown a flour sifter comprising a cylindrical casing or body 10 formed from a single piece of sheet metal having its edges overlapping and locked together, as indicated at 11 in Fig. 1. The casing or body 10 is provided with expanded ribs or beads 12 for the purpose of strengthening the body and is also provided with a groove 13 to receive and hold the rim or holder of the sifting screen.

The screen holder is of special construction, the details of which are clearly indicated in Figs. 5, 6 and 7. A rim or band 15 is first bent to the shape indicated in Fig. 5 and the screen 16 is bent to the semi-spheri-

cal shape shown in Fig. 1 but with its edge 55 portion turned outward and downward. The screen and band are then assembled in the relation indicated in Fig. 5 and the inner portion 17 of the band is bent upward and outward to the position indicated in 60 Fig. 6, thus binding the edge of the screen between the inner and outer portions of the band. The upwardly extending flange 18 of the band is then bent downward and inward, as indicated in Fig. 7, entirely enclosing and 65 protecting the edge of the screen.

In this way, a very substantial and reliable construction is provided which entirely encloses and protects the rough edges of the wire screen and which makes separation of 70 the screen and band practically impossible. The band or rim is of such diameter that it can be forced into the groove 13 but cannot easily be displaced therefrom.

The beater or agitator 20 is also of special 75 construction and comprises two circular rings of thin sheet metal placed at 90 degrees to each other and firmly secured in this position. For securing the parts together, we preferably form square perforations at both ends of each ring and also at a central point thereof, through which perforations eyelets 21 may be inserted, as indicated in Figs. 3 and 4.

These eyelets are also provided with 85 square openings 22 and are designed to fit a square shaft 23 by which the beater or agitator is supported and operated. The shaft 23 is bent at one end to support a handle 24 and the parts are retained in assembled 90 relation by upsetting or staking the end of the shaft 23 outward of the cylinder or body 10, as indicated at 25.

Each ring of the beater 20 is formed with a double bevel or approximately V section, 95 as indicated in Fig. 1. This construction greatly increases the strength of the ring and also provides an inclined surface which acts to force the flour toward the screen with either direction of rotation and thus increases the efficiency of operation.

A handle 26 is riveted or otherwise secured to the side of the body 10, this handle being preferably formed of sheet metal and having an inserted portion 27 (Fig. 8) secured between the folded edges of the handle before the end portions 28 thereof are bent to final position.

Having thus described our invention and the operation thereof, it will be evident that we have provided a flour sifter of greatly improved mechanical construction and operation, and it will also be evident that changes and modifications can be made in our invention without departing from the scope of the invention as set forth in the claims. Accordingly, we do not wish to be limited to the details herein disclosed, but what we claim is:

1. In a flour sifter, a removable dished screen and a cylindrical supporting band therefor, having a rib to interlock with the inner surface of the sifter body, the lower edge portion of the band being bent upwardly to form a clamping flange, said

screen being bent over the upper edge of said flange and between same and the body of said band, and the upper edge portion of said band being bent downwardly to engage the inner side of said screen and enclose the edge thereof, said folded band being substantially tangential to the main screen body.

2. In a flour sifter, a beater formed of two circular intersecting bands of sheet metal having non-circular perforations opposite each other at said intersections and having eyelets therein with non-circular openings to fit a supporting shaft.

In testimony whereof we have hereunto affixed our signatures.

PETER J. LEONARD.
FRED J. CONNOR.
